UNITED STATES PATENT OFFICE.

EDGAR COOKS, OF LOS ANGELES, CALIFORNIA.

DOOR-BED.

1,170,478.

Specification of Letters Patent. Patented Feb. 1, 1916.

Application filed April 8, 1914. Serial No. 830,026.

To all whom it may concern:

Be it known that I, EDGAR COOKS, a citizen of the United States, residing at Los Angeles, in the county of Los Angeles, State 5 of California, have invented new and useful Improvements in Door-Beds, of which the following is a specification.

This invention relates to a door bed, and particularly pertains to the mounting there- 10 for.

It is the object of this invention to provide a mounting for a folding bed, whereby the latter can be swung from one side to the other of a door opening independent of the 15 door, and be positioned parallel to the wall on either side thereof.

Another object is to provide a mounting for a folding bed, which will permit of its being swung in and out of a closet through 20 the door opening thereof, which will permit of the door opening being opened or closed both when the bed is in the room or in the closet without operating the bed mounting.

The invention primarily resides in a pair 25 of arm members pivoted on the inner face of the door casing, a pair of pivotally connected links pivoted to each of said arms, a folding bed frame carried by the outermost 30 of said links, and a planetary gear mechanism operating on the arms and links, whereby the bed may be swung from one side of a door opening to the other and be disposed parallel with the wall on either side thereof.

35 The invention is illustrated in the accompanying drawings, in which:

Figure 1 is a plan view of the bed and its mounting showing the bed in its folded position and as disposed within the closet and 40 with the closet door in its closed position. Fig. 2 is a corresponding view showing the closet door in its open position, and the bed as disposed in its intermediate position. Fig. 3 is a similar view showing the bed as 45 disposed in its outermost position in the room and the closet door closed. Fig. 4 is a detail section in elevation on the line 4—4 of Fig. 2, with portions broken away, illustrating the bed mounting. Fig. 5 is a de-

tail section and plan view on the line 5—5 50 of Fig. 4.

More specifically, 10 and 11 indicate the vertical jambs of a door opening 12 leading through a wall 13 and in this instance opening into a closet 14. The opening 12 is fitted with a sliding door 15 of peculiar construction and mounting to adapt it to the opening and closing of the door opening 12 irrespective of whether the bed is on one side of the wall 13 or the other. 60

The door 15 may be opened by swinging it outwardly in the ordinary manner with its rear edge adjacent the jamb 10. When it is desired to open this door to swing the bed through the opening as will be later described, the forward edge of the door is swung outwardly to clear the jamb 11 and it is advanced longitudinally along the exterior of the wall 13. 65

The bed mounting in which the essence 70 of the present invention resides, is particularly shown in Figs. 4 and 5 and includes a pair of parallel arms 27 and 28 provided with pivot pins 29 and 30 and pivoted to swing horizontally on the door jamb 10; the 75 pivot pin 29 being journaled in a socket 31 formed in a plate 32 secured to the floor 33 adjacent the jamb 10 by means of screws 34, and the pivot pin 30 being journaled in a bracket 35 secured to the jamb 10 at a 80 suitable point above the floor by means of screws 36.

The arms 27 and 28 are connected together so as to rock synchronously; the connection between the arms 27 and 28 comprising a 85 vertically extending rod 37 which is connected at its ends to lugs 38 and 39 formed on the arms 27 and 28 respectively, in such position that the axes of the pivot pins 29 and 30 and the rod 37 will be aligned. Pivoted on the arms 27 and 28 with their pivotal connections in vertical alinement are links 90 40 and 41, the outer ends of which are connected together by means of a rod 42; the ends of the rod 42 being rigidly connected 95 to bosses 43 and 44 formed on the links 40 and 41 respectively. The rod 42 extends parallel with the rod 37 and the links 40 and

41 connected thereby are of such length that the rod 42 and the links may be swung on their pivots from one side of the rod 37 to the other with the links extending toward 5 the rod 17.

The pivotal mounting of the link 41 consists of a simple pivot pin 45 and the pivotal mounting of the link 40 consists of a trunnion 46 journaled in a bracket 47 carried on the arm 27 and a shaft 48 formed on the underside of the link 40 in axial alignment with the trunnion 46 and journaled in the arm 27 and extending therethrough.

Pivots mounted on the bosses 43 and 15 44 on the ends of the links 40 and 41 are short links 49 and 50, the outer ends of which are formed with aligned saddles 51 and 52 for the reception of the horizontal top and bottom rails 53 and 54 of a rectangular frame 55 which is carried by the links 20 49 and 50 and is rigidly attached thereto by means of bolts.

The frame 55 comprises the head of a folding bed 57 which may be of any suitable construction and adapted to be swung vertically in relation to the frame 55 from a horizontal to a vertical position. The folding bed 57 may be of any suitable type and forms no part of the present invention, 30 other than that the bed mounting is provided for removably supporting beds of the vertical folding type.

When the bed is in the closet 14, as shown 35 in Fig. 1, the arms 27 and 28 will extend into the closet at right angles to the jamb 10; the bed frame 55 will be disposed parallel with the wall 13 with the links 49 and 50 extending at right angles thereto, and the links 40 and 41 connecting the links 49 and 50 to 40 the arms 27 and 28 extending at right angles thereto.

It will now be seen that the bed is carried on a series of three independently pivoted members which would ordinarily permit the 45 bed being swung into various positions on each member independent of the other members, and would readily permit its being moved back and forth through the door opening 12 from one side of the partition to the other in any desired position within the 50 range of movement of the pivotally connected members. While this could be effected through the mechanism described, intricate and inconvenient movements of the 55 various parts in relation to each other would be necessary. Therefore, means are provided by which the several pivoted members will be caused to move in defined paths of travel in relation to each other on movement of any one of their number so that in 60 swinging the bed into its several positions the operator need only effect one operation, namely, pulling the bed frame in a general direction. This is accomplished by the use

of a planetary gear system of peculiar construction, comprising a circular rack 58 formed on the link 49 which meshes with an idler pinion 59 revolvably mounted on a stud 60 carried by the link 40, which pinion meshes with an arcuate toothed rack 61 65 formed on and preferably integral with the bracket 47 carried by the arm 27; a toothed wheel 62 rigidly mounted on the shaft 48 beneath the arm 27 meshing with an idler pinion 63 revolvably mounted on a stud 64 70 carried by the arm 27, which pinion meshes with a curved rack 65 formed on the outer vertical face of the plate 32.

In the operation of the invention assume the parts to be positioned as shown in Fig. 1, 80 in which the bed is illustrated as disposed in a closet with the door 15 closed. To gain access to the closet for ordinary purposes this door 15 may be swung in the manner common in ordinarily hinged doors, but 85 when it is desired to move the bed into the room through the door opening this door is swung, moved so that it will be disposed alongside the wall 13 adjacent the jamb 11. The bed frame 55 is then pulled in the direction indicated by the arrow —a— in Fig. 1, which causes the arms 27 and 28 to swing synchronously on their pivots 29 and 30 in the direction indicated by the arrow —b— in Fig. 1. This causes the idler pinion 63 on 90 the arm 27 to travel over the rack 65 and be rotated thereby in the direction indicated by the arrow —c— in Fig. 1 so as to cause the gear wheel 62 to rotate in the reverse direction as indicated by the arrow —d— in 95 Fig. 1, which in turn operates the shaft 48 to rock the links 40 and 41 inwardly in the direction indicated by the arrow —d—; the links 40 and 41 thus moving into a position parallel with the arms 27 and 28 when the 100 latter are positioned parallel with the wall 13 in the door opening 12 as illustrated in Figs. 2 and 4. This inward movement of the links 40 and 41 toward the arms 27 and 28 causes the pinion 59 on the link 40 to travel 110 over the rack 61 carried by the arm 27 to rotate the pinion 59 in the direction indicated by the arrow —f— in Fig. 1, which in turn causes the rack 58 to turn in the direction of the arrow —e— in Fig. 1, thus 115 rocking the links 49 and 50 toward the links 40 and 41 to turn the bed frame 55 carried thereon in the direction indicated by the arrow —h— in Fig. 1 so that the bed will be disposed crosswise of the opening 12 when 120 in its intermediate position as shown in Fig. 2. Continued movement of the bed frame will swing the arms 27 and 28 to extend to the opposite side of the partition 13, as shown in Fig. 3; this movement also causing 125 the links 40 and 41, and 49 and 50 to move into such position that the bed will be disposed parallel with the wall 13 in the

room. When this has been accomplished the door 15 can be moved to its closed position and opened, as occasion may require.

From the foregoing it will be seen that the bed carrying frame 55 may be readily swung in and out of the closet 14 through the door opening 12, the intermeshing planetary gears operating to direct the pivotal movement of the bed frame over a defined path of travel either in moving into or out of the closet.

What I claim is:

1. In a folding bed mounting, the combination of a pair of parallel spaced arm members, a link pivoted to each of said arms, a second link pivoted to the first-named link a folding bed frame carried by the second-named link, and a planetary gear mechanism adapted to operate on the arms and links, whereby the bed may be swung from one side of a wall to the other on a definite line of travel and be disposed parallel with the wall on either side thereof.

2. A folding bed mounting, comprising a pair of parallel spaced arm members, a link pivoted to each of said arms, a second link pivoted to the first-named link a bed frame carried by the second-named links, a stationary circular rack, a pinion on one of the arms engaging said rack, a toothed wheel carried by the last-named arm engaging said pinion and rigidly connected to the link carried by said arm, a rack rigidly mounted on said arm, a pinion on one of said links engaging said last-named rack, and a rack carried by the link connected to the pinion carrying link engaging the pinion thereon, said racks and pinions adapted to operate to direct the movements of the links and arms on a definite path of travel.

3. The combination with a bed frame, of a pair of links to which said bed frame is rigidly mounted, a pair of pivoted arms, link connections between said arms and the before-mentioned links, and a planetary gear mechanism adapted to operate on said arms and links, whereby swinging of any one of the arms or links will effect a swinging movement of the other arms and links in a definite path of travel.

4. A mounting for folding beds, comprising a pair of connected arms, pivotal supports for said arms, connected links pivotally mounted on the outer ends of said arms, bed supporting links pivotally connected to the before-mentioned links, a rack carried by one of said last-named links, a rack carried by one of said arms, an idler pinion carried on one of the first-named links meshing with both of said racks, a toothed wheel connected to a pinion carrying link, a stationary rack, and a pinion carried by one of said arms connecting said toothed wheel and stationary rack.

5. A folding bed mounting, comprising the combination with a door casing, of a pair of connected arms pivoted to the casing, a pair of connected links pivoted to said arms, a bed frame pivotally connected to said links, and gear means acting on the arms and links whereby rocking of said arms will effect a movement of the bed frame in a definite path of travel by which the bed frame may be moved from one side of the door casing through a door opening to the opposite side thereof.

6. A folding bed mounting comprising the combination with a wall having an opening therein, of a pair of arms pivoted near one side of the opening, a bed frame, pivotal connections between said bed frame and arms, and a gear mechanism acting on said arms and pivotal connections for controlling the movements of the bed frame and arms in relation to each other.

7. A folding bed mounting comprising the combination with a wall having an opening therein, of a pair of spaced arms pivoted near one side of the opening, an arcuate toothed rack arranged concentric with the pivotal mounting of one of said arms, a bed-supporting frame mounted on the outer ends of said arms for swinging movement in relation thereto, and gear mechanism engaging said rack and acting on the bed-supporting frame, whereby the rocking of said arms will effect a swinging movement of the bed-supporting frame in a definite path of travel.

8. A folding bed mounting comprising a pair of spaced arms, vertically-aligned pivotal mountings for said arms, an arcuate toothed rack rigidly mounted concentric with the pivotal mounting of one of said arms, a link carried by each of said arms, a bed-supporting frame mounted to swing in relation to said links, and gear mechanism operated on by said arcuate rack and acting on said links and bed-supporting frame, whereby the swinging of the frame will effect movement of the frame, links and arms in a definite path of travel.

9. In a bed mounting, an arm mounted to swing horizontally, a link pivoted on the outer end of said arm, a second link pivoted on the outer end of the first-named link, bed-supporting means carried by said second link, and gear mechanism acting on said arms and links, whereby swinging of the arm or either of the links will effect a movement of the bed-supporting means in a definite path of travel.

10. In a bed mounting, an arm pivoted to swing horizontally, a stationary curved rack arranged concentric with the pivot of said arm, a shaft revolvably mounted on the outer end of said arm, a toothed wheel mounted on said shaft, an idler pinion revolvably mounted

on said arm meshing with said toothed wheel and with the curved rack, an arcuate toothed rack carried by said arm arranged concentric with said shaft, a link formed on 5 said shaft, an idler pinion carried by said link meshing with the arcuate toothed rack, a second link pivoted on the outer end of the first-named link, a toothed rack on said second link concentric with its pivot meshing 10 with the idler pinion on the first-named link,

and bed-supporting means carried by said second link.

In witness that I claim the foregoing I have hereunto subscribed my name this 23rd day of March, 1914.

EDGAR COCKS.
